Fig. 7.

Fig. 6.

Fig. 5

FIGURE 1 is a top plan view of a lawn sprinkler, showing our new design;

FIGURE 2 is a side elevational view thereof;

FIGURE 3 is a front elevational view thereof;

FIGURE 4 is a rear elevational view thereof;

FIGURE 5 is an enlarged, fragmentary sectional view taken along the line 5-5 of FIGURE 2;

FIGURE 6 is an enlarged, fragmentary sectional view taken along the line 6-6 of FIGURE 1; and

FIGURE 7 is an enlarged, fragmentary sectional view taken along the line 7-7 of FIGURE 1.

We claim:

The ornamental design for a lawn sprinkler, as shown.
